UNITED STATES PATENT OFFICE

RICHARD W. STEWART, OF AUBURN, NEW YORK

RIFLE RANGE

Application filed April 23, 1928. Serial No. 272,185.

This invention consists of a new and improved amusement device and is primarily designed to produce a unitary apparatus which may be used in shooting at targets.

5 In the ordinary shooting gallery in which persons may exercise their skill in shooting at targets with guns it is necessary to provide a considerable amount of space and a very considerable amount of equipment. It 10 is also necessary to have attendants in charge of the equipment and of the clientele.

The main object of my invention is to provide a unitary structure which is a complete shooting gallery in itself but which may be 15 transported from place to place and which will require an inconsiderable amount of space for its operation.

Another object is to provide a structure which may be utilized by customers without 20 requiring that an attendant be in charge of the operation of the device.

Another object is to provide a structure which can be operated solely by the customer and in which payment for the use of the 25 device may be automatically received by the device itself.

Other objects and advantages relate to the size, shape and arrangement of parts all as will more fully appear from the following 30 description taken in connection with the accompanying drawings in which:

Figure 1 is a perspective view of my device.

Figure 2 is a section on line 2—2 of Figure 35 1.

Figure 3 is a section on line 3—3 of Figure 1.

Figure 4 is a section on line 4—4 of Figure 40 3.

Figure 5 is a section on line 5—5 of Figure 4.

Figure 6 is a section, partially broken away, on line 6—6 of Figure 1.

45 Figure 7 is a section, partially broken away, on line 7—7 of Figure 2.

Figure 8 is a section on line 8—8 of Figure 2.

50 Figure 9 is a section, partially broken away, on line 9—9 of Figure 2.

Figure 10 is a section on line 10—10 of Figure 6.

Figure 11 is a section on line 11—11 of Figure 6.

Figure 12 is a section on line 12—12 of 55 Figure 10.

Figure 13 is a section on line 13—13 of Figure 6.

Figure 14 is a section, partially broken 60 away, on line 14—14 of Figure 6.

Figure 15 is a section on line 15—15 of Figure 3.

It will be understood that the size and shape of the cabinet which I use with my device may be varied to a considerable extent, 65 as desired, but for the purpose of explaining the construction and association of the parts of my structure, I have here shown a cabinet —1— substantially rectangular in longitudinal cross-section, and having at the upper 70 and longitudinal edge of one side a glass covered opening —2—, and a second glass covered opening —3— in the upper edge of one end of the cabinet —1—.

On the inner face of the end of the cabinet 75 —1— which is opposite the opening —3—, I provide a plurality of (in this case shown as three) fixed targets —4— in spaced relation. As perhaps may best be seen from Figure 9, these targets consists of a circular 80 plate —5— affixed to a support —6— and carrying on the rear face a bell or gong —7— which is made to reverberate by the impact of a bullet if the same passes through an aperture 5' positioned in the center of the 85 target —4—. I also provide preferably below and in parallel relation to the targets —4— a plurality (in this case shown as thirty) of movable targets —8—, which in this instance I have shown as being assembled in two parallel rows of fifteen targets 90 each.

The construction and operation of targets 95 —8— may perhaps best be seen from Figures 2 and 7. The targets —8— are of similar construction, and a description of one is a description of them all. The target —8— consists of a circular disk —9— supported on a rod —10—, which rod —10— is rotatably mounted on a shaft —11—. Shaft —11— 100

in turn is journaled in the opposite ends of a bracket —12— affixed by screws —13— or other convenient means to the end wall of cabinet —1—. Rod —11— carries at each 5 end and adjacent the inner faces of bracket —12— circular disks —13'— and —14— rigidly affixed to shaft —11—. The ends of the rods —10— which are mounted on shaft —11— have adjacent each face a circular disk —15— free to rotate on shaft —11—.

I provide between disk —13'— and the next adjacent disk —15— a spiral spring —16— encircling shaft —11—. I also provide between each of the rods —10— spiral springs —17— which encircle shaft —11— and at the opposite end of shaft —11— I provide a spiral spring —18— encircling shaft —11— and positioned between disk —14— and the next adjacent disk —15—. The tension of springs —16—, —17— and —18— is such that the rods —10— are normally held in fixed relation to shaft —11—.

On the end of shaft —11— outside of one end of bracket —12— a pulley —19— is fixed 20 to shaft —11— and adjacent pulley —19— a ratchet wheel —20— is fixed to shaft —11—.

Adjacent sprocket —20— is a lever —21— rotatably mounted on shaft —11— and carrying a pivoted pawl —22— coacting with sprocket —20— and normally held in mesh with sprocket —20— by means of spring —23—.

The description of the assembly of targets —8— which has just been given refers to 35 one row of such targets. The other row of targets —8— which is disposed in parallel relation to the first-mentioned row is constructed in a similar manner except that it is not provided with the ratchet —20— and the lever —21— and pawl —22— and spring —23—. The two shafts —11—, however, are operatively connected by means of a belt —24— encircling the two pulleys —19—.

At the upper end of lever —21— I provide 45 a pull-rod —25— which extends longitudinally of cabinet —1— to the outside of the end of cabinet —1— which carries the opening —3—. Pull rod —25— is provided at its outer end with a handle —26— so that 50 it may be conveniently manually pushed in and out of cabinet —1—.

As perhaps may best be seen from Figures 1 and 6 I provide in the end of cabinet —1— which carries aperture —3— and positioned 55 below aperture —3— a plate —27— having a circular aperture —28— in its upper end and a second circular aperture —29— below aperture —28—.

60 A rifle or gun —30— (it being understood that the particular design or construction of the rifle —30— is immaterial, except that it is desirable to have it of a type in which the propelling of the bullet is accomplished by 65 either air or spring pressure) is positioned

with its barrel —31— extending through aperture —28— into cabinet —1—.

An L-shaped bracket —32— has one arm positioned against the inner face of plate —27— with the other arm extending outwardly through aperture —29— and with the end of the last mentioned arm pivotally mounted on the under side of breach —33— of rifle —30— by means of a pivot pin —34—.

It will be understood that this assembly of rifle —30— in plate —27— is such that the barrel —31— of rifle —30— will be held within cabinet —1— at all times, but rifle —30— is free to move vertically or laterally so that the end of barrel —31— may be pointed towards any of the targets —4— or —8— as desired.

For the purpose of supplying bullets (not shown) to rifle —30— I provide in cabinet —1— a hopper —35— suspended from the cover —36— of cabinet —1— and positioned above rifle —30—. As perhaps may best be seen from Figures 10, 11 and 12, hopper —35— consists of a substantially square body having a bottom which slopes downwardly from both sides, as indicated at —a— and —b— in Figure 11, towards a discharge opening —36—. The discharge opening —36— is provided with a movable cover —37—, which cover is provided adjacent one end with a plurality, in this case shown as fifteen, of circular apertures —38— of a size to permit the passage therethrough of bullets (not shown).

The apertures —38— are arranged in echelon on one longitudinal edge of movable cover —37— so that when the cover —37— is moved with relation to the discharge opening —36—, the apertures —38— will pass beyond the end of discharge opening —36— in rotation.

At one end of discharge opening —36— I provide an inclined trough —39— so positioned with relation to movable cover —37— and discharge opening —36— that when movable cover —37— carrying apertures —38— is moved in relation to discharge opening —36— apertures —38— each carrying a bullet (not shown) will be moved beyond discharge opening —36— and into registration with trough —39—, permitting the bullets carried in the apertures —38— to be discharged into trough —39—.

It will be understood that a supplementary fixed cover —40— is positioned under discharge opening —36— to act as a support and guide for movable cover —37— and also to insure the retention in apertures —38— of the bullets until the apertures —38— have been moved beyond the end of cover —40—.

The purpose of positioning the apertures —38— in echelon is so that when they are moved into registration with trough —39—, the bullets will drop into trough —39— in rotation and there will be no possibility or

liability of their becoming jammed so that they will not move downwardly in the trough —39—.

At the bottom end of trough —39— I provide a spout —41— in communication with trough —39— for the reception of the bullets. Spout —41— carries at its lower discharge end —42— a flexible tube —43— preferably made of spirally wound wire and having its opposite end in communication with the magazine —44— of rifle —30—. The length of flexible tube —43— is such that it does not interfere with the free movement of barrel —31— in cabinet —1—.

In the discharge opening —36— are positioned a plurality of baffle plates —44'— in parallel spaced relation and so positioned in relation to apertures —38— that bullets in the hopper —35— will be guided so that they will enter apertures —38—.

Bottom plate —37— is so positioned with relation to discharge opening —36— that a limited movement of bottom plate —37— towards trough —41— is permitted before apertures —38— pass beyond discharge opening —36—.

A lever —45— is pivotally mounted on the end of cabinet —1— by a pivot pin —46—. The upper end of lever —45— enters a slot —47— in bottom plate —37— so that the movement of the lever —45— about its pivot —46— will move bottom plate —37— back and forth in relation to discharge opening —36—.

The bottom end of lever —45— is positioned as may best be seen from Figure 15 in a slot —47'— in the end of a control rod —48—. Control rod —48— is guided in a bracket —49— secured to one end of cabinet —1— and is secured at the end opposite slot —47'— to a push rod —50— by rivet —51— or other convenient means. Push rod —50— at its other end is pivotally connected to an automatic coin device —52— consisting of a top plate —53— in which is pivotally mounted for vertical movement a detent —54—. A spring —55— is secured in top plate —53— by screw —56— and normally forces detent —54— beneath the under surface of top plate —53—. Top plate —53— is secured to the upper surface of a slotted member —57— by screws —58— or other convenient means.

Slotted member —57— has an elongated aperture —59— positioned under top plate —53—. A slide —60— is positioned in slotted member —57— and is connected at its inner end by means of a link —61— to the end of push rod —50—. Slide —60— has an aperture —62— of a size and shape to receive a five cent U. S. coin.

When slide 60 is pulled outwardly from the side of cabinet —1— the aperture —62— is outside of cabinet —1—. This outward movement of slide —60— through link —61—, push rod —50— and control rod —48— will

move the bottom end of lever —45— forwardly and the upper end of lever —45— backwardly, which draws bottom plate —37— in such a relation to discharge opening —36— that apertures —38— are inside of discharge opening —36—.

The outward movement of slide —60— will cause the inner upper surface of slide —60— to contact with detent —54— and move the same upwardly against the pressure of spring —55—. If slide —60— is then pushed inwardly with no U. S. five cent coin in aperture —62—, detent —54— will be forced downwardly by spring —55— into aperture —62— and detent —54— will contact with the outer edge of aperture —62— to limit any further inward movement of slide —60—. In this position the forward end of slot —47— has just come in contact with the lower end of lever —45— but has caused no movement of lever —45— so that the position of bottom plate —37— is unaffected. If, however, a five cent U. S. coin is placed in aperture —62— before slide —60— is pushed inwardly, the detent —54— will pass from the upper surface of slide —60— onto the upper surface of the U. S. five cent coin and thence on to the outer upper surface of slide —60— and will not interrupt the continued inward movement of slide —60— so that after the forward edge of slot —47— contacts with the bottom end of lever —45— the continued inward movement of slide —60—, link —61—, push rod —50— and control rod —48— will

cause the bottom end of lever —45— to be moved backwardly and the upper end of lever —45— to be moved forwardly, with the result that bottom cover —37— will be moved in relation to discharge opening —36— and apertures —38— will be moved outwardly from discharge opening —36— into registration with trough —39— to permit the depositing therein of the bullets carried in apertures —38— so that such bullets may then move downwardly from trough —39— into spout —41— and flexible tube —43— so that they will be in a position to be fed by gravity into magazine —44— of rifle —30—.

When it is desired to discharge a bullet from rifle —30— the finger lever —63— of rifle —30— is pulled forwardly and downwardly in the manner well known to the art, which movement of finger lever —63— will cause the retraction in barrel —31— of piston —64— against the action of spiral spring —65— which encircles the body of piston —64—. This rearward movement of piston —64— will cause plunger —66—, which is carried on the forward end of piston —64—, to be retracted in barrel —31— a sufficient distance to permit the movement of a bullet from flexible tube —43— into barrel —31—.

In order to retain the bullet in proper position in the barrel —31— and to prevent its

moving forwardly by gravity out through barrel —31— in case the forward end of barrel —31— should happen to be pointed downwardly, I provide a ball —67— in an aperture —68— in one side of barrel —31— normally held by a spring —69— so that a portion of ball —67— extends into barrel —31— in the path of the bullet so that the same cannot move forwardly in the barrel —31— until the plunger —66— forces it against the ball —67— which by such action is forced out from aperture —68— against the pressure of spring —69—.

When the piston —64— has been retracted, as just described, finger lever —63— is returned to the normal position and the rifle —30— is then in such a condition that the retraction of the trigger —70— will release piston —64—, and plunger —66— will force the bullet out from the barrel —31— with a velocity depending upon the strength and resiliency of the different parts of the operating mechanism.

The object of the apparatus is to afford the user an opportunity to strike selected targets —4— and —8—. When a target —4— is struck, the target is unaffected. When a target —8— is struck, it will be pivoted about the shaft —11— against the resistance of the springs —16—, —17— and —18— and will disappear from view behind a bracket —12—.

When it is desired to replace targets —8— in position, rod —25— is pulled outwardly by means of handle —26—, with the resulting pivotal movement of lever —21— and the rotation thereby through pawl —22— of ratchet wheel —20— and shaft —11—. The targets —8— which have been knocked down will by this rotation of shaft —11— be moved upwardly until they contact with bracket —12— to prevent further forward movement. The targets —8— which were initially upright will remain in that position, the shaft 11 rotating in the rods —10— which support them.

In order that the bullets which have been expelled from the rifle —30— may be easily collected for future use, I provide in cabinet —1— a pair of downwardly sloping opposed shelves —71— and —72— in parallel spaced relation and joined together by a sloping trough —73— which discharges into a box —74— through spout —75—. I also provide a box —76— positioned beneath aperture —59— so that when slide —60— carrying a five cent U. S. coin has been pushed inwardly until aperture —62— registers with aperture —59—, the coin will drop downwardly into the box —76—.

In order that boxes —74— and —76— may be removed from cabinet —1— I provide in the back thereof a door (not shown). For the purpose of filling hopper —35— from time to time with a new supply of bullets I

provide a covered opening —77— in the top of cabinet —1— and positioned over the upper and open end of hopper —35—.

This arrangement and association of parts provides an apparatus which can be used and enjoyed by a customer without any assistance. The only attention which my apparatus requires from those who may be in charge of it is the replenishment from time to time of hopper —5— with a supply of bullets, and in consequence devices of this construction may be placed in different places of amusement and a great number of them may be taken care of by a single custodian.

In describing a specific structure embodying my invention I have shown a particular size and shape of parts and a particular arrangement of the same with relation to each other, but it will be understood that the materials of which my structure is made and the exact size and shape of the different parts thereof may be varied without departing from the spirit of my invention, for altho I have shown and described a specific structure and form of part as an exemplification of an embodiment of my invention, I do not desire to restrict myself to the exact shape, size or arrangement of parts, as various changes may be made within the scope of the appended claims.

What I claim is:

1. In a device of the class described, a cabinet, a plurality of targets secured in one end of the cabinet, a window in the opposite end of the cabinet, a rifle movably mounted on the cabinet, a hopper, a supply of bullets in the hopper, a movable bottom for the hopper, a plurality of apertures positioned in echelon on one edge of the bottom for the reception of bullets, a trough secured to the bottom of the hopper, a flexible conduit connecting the trough and the rifle, and means for moving such bottom whereby the bullets in the apertures are moved out from the hopper and deposited in the trough for movement through the flexible conduit to the rifle.

2. In a device of the class described, a cabinet, a plurality of targets affixed to one end of the cabinet, an aperture in the opposite end of the cabinet, a bracket pivotally mounted on the cabinet beneath the aperture, a rifle pivotally mounted on one end of the bracket and having its barrel extending through the aperture into the cabinet, a hopper positioned in the cabinet, a plurality of bullets in the hopper, and means for transferring bullets from the hopper to the rifle.

3. In a device of the class described, a cabinet, a plurality of targets secured to one end of the cabinet, an aperture in the opposite end of the cabinet, a rifle movably mounted in the aperture, a hopper having a constricted discharge opening mounted in the hopper, a movable cover for the constricted open-

ing, a support for the movable cover having a depending trough at one edge, a plurality of apertures in the movable cover disposed in echelon with reference to an edge thereof, 5 said apertures being each of a size and shape to receive and retain a bullet, a plurality of bullets in the hopper, means for moving the movable cover with relation to the constricted opening whereby the apertures in the movable cover may be moved over the trough to permit deposit of the bullets carried by them in the trough, and a flexible conduit connected to the trough and to the rifle.

10 4. In a device of the class described, a cabinet, a plurality of targets secured to one end of the cabinet, an aperture in the opposite end of the cabinet, a rifle movably mounted in the aperture, a hopper having a 15 constricted discharge opening mounted in the hopper, a movable cover for the constricted opening, a support for the movable cover having a depending trough at one edge, a plurality of apertures in the movable cover disposed in echelon with reference to 20 an edge thereof, said apertures being each of a size and shape to receive and retain a bullet, a plurality of bullets in the hopper, a plurality of baffle plates in the hopper dis- 25 posed to direct bullets into the apertures, means for moving the movable cover with relation to the constricted opening whereby the apertures in the movable cover may be moved over the trough to permit deposit of 30 the bullets carried by them in the trough, and a flexible conduit connected to the trough and to the rifle.

35 In witness whereof I have hereunto set my hand this 17th day of April, 1928.

40 RICHARD W. STEWART.
